UNITED STATES PATENT OFFICE.

CHARLES E. LUCE, OF STUTTGART, GERMANY.

METHOD AND APPARATUS FOR EFFECTING GOLD OR TIN DENTAL STOPPINGS.

Application filed March 9, 1923. Serial No. 624,034.

To all whom it may concern:

Be it known that I, CHARLES E. LUCE, a citizen of the United States of America, residing at 32 Staffenbergstrasse, Stuttgart, 5 Germany, have invented certain new and useful Improvements in Methods and Apparatus for Effecting Gold or Tin Dental Stoppings, of which the following is a specification.

10 The methods hitherto usually employed for the effecting of dental stoppings with gold, or other materials, have a number of serious disadvantages which make their employment difficult. Thus, gold stoppings in 15 particular can only be effected with an expenditure of considerable trouble, skill and time; besides which, the patient is subjected to much discomfort. According to the most usual method, the gold-foil is first heated 20 red-hot and then worked piece by piece into the tooth-cavity with gold-stopping instruments and hammered into place; such stoppings are seldom homogeneous or hermetic. Another method that is employed, the so-called casting method, has, in addition to 25 the disadvantages mentioned, the drawback that only rarely is a perfectly fitting stopping attained and moreover, the gold stopping has finally to be cemented into the cavity of the tooth. Now the present invention relates to a method which entirely obviates 30 all these disadvantages. It is based on the idea that pure gold, freshly heated red-hot, becomes cohesive and is for some time capable of cold welding. The method, according to the invention, is carried out in 35 the following manner. Finely divided gold, preferably very thin dental-foil, in the form of very tiny flakes, is drawn by 40 suction through a quartz-glass tube, which is heated to incandescence and by means of compressed air, or some other medium, is conducted into the tooth-cavity until the latter is completely filled; it is clear that 45 each tiny flake, or particle of gold, will be heated red-hot while passing through the incandescent quartz-glass tube and thus be annealed and rendered cohesive and capable of cold welding. The particles of gold 50 which have been heated red-hot and rendered cohesive are conducted onwards by the compressed air, or other medium and thrown on to the desired point by means of a suitable mouth-piece. As soon as they encounter 55 a resistance, they lie flat, through the air pressure, one on the other and mutual-

ly weld together. By means of this method, according to the present invention, it is possible to give the gold application any form or thickness and in the same manner stoppings of tin, or a mixture of gold and tin, may be effected. The stoppings effected in this manner fit exactly in the cavity in the tooth and the expenditure of time is exceedingly small compared with that involved in any of the methods hitherto employed. Particular skill is, moreover, not necessary for insuring perfectly satisfactory results and the effecting of such stoppings proceeds with little discomfort to the patient.

An apparatus for carrying out the process is illustrated in the drawing, in side elevation, in one example of construction.

75 Finely divided gold is put into a receptacle *a*, which can be placed in communication with a compressed-air pipe *c*, by means of a valve *b*, below. The receptacle *a* communicates above with a device which enables the particles of gold to be heated, annealed and 80 made cohesive. In the example of construction shown, the device consists of a quartz-glass tube *d*, which is heated to incandescence by means of an electric current, and through which the particles of gold conveyed from the receptacle *a*, through a pipe *e* are conveyed and heated red-hot and thereby rendered cohesive. The particles of gold are conducted from the quartz-glass tube *d*, through a pipe *f*, to the place where 85 they are employed. For this purpose, a flexible tube which terminates in a nozzle-like mouthpiece and attached to the pipe *d*, is indicated.

90 The pressure pipe, moreover, is directly connected with the pipe *f*, in order that it may be possible to exercise a suctional action in the receptacle *a*, for which purpose an opening *i* is provided in the cover *h*. Thereby with the assistance of the compressed air 95 in the receptacle *a*, it is possible to produce a suctional action in the receptacle *a*, by means of which the particles of gold are drawn through the heating device *d* and into the pipe *f*, in which they are then carried 100 by the compressed air to the place where they are employed. In order to effect an adequate suction of gold particles, some of the latter are set into active motion by opening the valve *b*.

105 The formation and details of the apparatus are optional. The method may be em-

ployed also for other purposes besides dental stoppings.

I claim as my invention:

1. An apparatus for treating and delivering gold dental stoppings, comprising a receptacle for the material in a finely divided condition, a pressure conduit for delivering the material in its original finely divided condition from the receptacle directly to the tooth, and means for heating the material during such delivery to render the particles of the material cohesive, said heating means forming a part of said conduit.
- 10 2. An apparatus for treating and delivering gold dental stoppings, comprising a receptacle for the material in a finely di-

vided condition, a pressure conduit for delivering the material in its original finely divided condition from the receptacle directly to the tooth, and means for heating the particles of the material cohesive, said heating means forming a part of said conduit, and a by-pass forming a part of said pressure conduit, and leading around the receptacle and heating means.

In testimony whereof I affix my signature in presence of two witnesses.

CHARLES E. LUCE.
